UNITED STATES PATENT OFFICE.

KOLOMAN RÓKA, OF CONSTANCE, GERMANY, ASSIGNOR TO THE FIRM OF HOLZVER-KOHLUNGS-INDUSTRIE AKTIEN-GESELLSCHAFT, OF CONSTANCE (BADEN), GERMANY, A CORPORATION OF GERMANY.

PROCESS OF CHLORINATION OF METHANE.

No Drawing. Application filed October 14, 1921, Serial No. 507,755, and in Germany October 18, 1920.

The known processes for chlorinating methene can be divided into two groups, viz:

(a) those which work at low temperature and in which the energy required for the initiation and for the maintenance of the reaction has the form of light or the form of electric energy (silent electric discharges),

(b) those which are carried out at high temperature, in which the energy is supplied 10 in the form of heat.

With both working methods it is necessary to moderate the reaction which takes place under strong development of heat, eventually under explosion by the addition of a diluent.

15 As such diluent, nitrogen or carbon dioxide has been proposed mainly or one of the components of reaction itself. Steam has been proposed also as a diluent but only for the "light methods" carried out at very low temperature for instance 80-100° C. (see *Chemisches Zentralblatt* 1913, II, page 99) which permit the unobjectionable application of this diluent.

For the "heat methods" which are carried 25 out at high temperatures, for instance 400-500° C., the use of steam as diluting agent seemed however to be excluded from the beginning as it is known that at these temperatures chlorine and steam act on each other 30 very rapidly with the formation of oxygen. Applicant has now made the surprising observation that the harmful reactions do not occur. As has been found out, the chlorine seems to possess a selective affinity so that 35 it does not attract the hydrogen of the steam but the hydrogen of the methane. The undesired reaction

40 consequently does not take place but surprisingly the process goes on smoothly in the desired direction for instance

45 The steam does therefore unexpectedly not participate in the reaction, despite the high temperature, but it exerts merely the desired retarding effect.

Even the decomposition of the product of 50 chlorination by the steam present which could be expected on account of the high reaction temperatures does not take place as has been ascertained.

In order to make the desired reaction suc-

cessful and to avoid undesired secondary reactions it is necessary to watch the temperature because at excessively high temperatures the undesired decomposition of water will take place and carbonic acid and carbonic oxide are obtained in the exit gases. The percentage of steam can vary within considerable limits. Generally the use of 2 to 3 volumes of steam for one volume of chlorine has proved to be sufficient. In certain cases even an addition of 1 to 2 volumes of steam will be sufficient and under certain conditions even a still smaller addition. There are theoretically no upper limits for the addition of steam but for practical reasons it is advisable to avoid the addition of larger quantities than necessary. For any given unit of apparatus, the maximum temperature, the correct quantity of steam and the maximum speed of the gases can be easily ascertained by simple gas analysis (determination of carbonic dioxide and carbonic oxide).

The use of steam offers in comparison with the use of gases such as nitrogen and carbonic acid the advantage, that no foreign gases are introduced into the product of reaction. Over the use of these gases or of methane in excess there is further realized a progress in so far as a much smaller excess of steam is required to absorb the liberated heat and to remove the same. Another essential advantage consists in this that the isolation of the product of chlorination, e. g. of the methyl chloride from the gases of reaction is effected in a simpler manner than hitherto as it is merely necessary to condense the steam which is not present in large quantities, while with the known processes the isolation of the methyl chloride by compression and cooling becomes the more complicated and the more detrimental, the greater the quantity of the diluting agent employed, e. g. methane. As now extraordinarily great quantities of methane in excess are required just for the production of a principal product of chlorination, methyl chloride, the advantage of the utilization of steam is quite obvious. A further advantage over the process which works with methane excess consists in the possibility of regulating according to the improved process the proportion of chlorine and methane in accordance with the products of chlorination which are to be obtained.

Other diluting means, for instance meth-

- ane, can however be used besides the steam, in which case the advantage is obtained that much smaller quantities of these auxiliary diluting means are required than hitherto.
5. The process can be carried through as well in the presence and in the absence of catalyzing agents, such as cupric chloride, ferric chloride and others. The halides of the alkaline earths, for instance chloride of calcium, 10 chloride of magnesium and others, have been shown to be very efficient catalyzing substances; they could be used eventually with convenient diluting means for instance upon porous carriers.
15. It has been found out further that the steam can be utilized simultaneously to introduce into the reaction space the heat required for the reaction from which results the advantage that no heating from the outside is 20 necessary, thereby simplifying the plant.
- I claim:—
1. In the heat method of chlorinating methane, the steps which comprise chlorinating methane in the presence of steam as a diluent at a temperature of 400°-500° C., and keeping the temperature below that at which substantial quantities of oxides of carbon are formed. 25
  2. In the heat method of chlorinating methane, the steps which comprise chlorinating methane at a temperature of 400°-500° C. in the presence of steam as a diluent and a chlorination catalyst, and keeping the temperature below that at which substantial quantities of oxides of carbon are formed. 30
  3. The process as in claim 2 in which the catalyst is a halide of an alkaline earth metal. 35
  4. The process as in claim 2 in which the catalyst is calcium chloride.

In testimony whereof I have signed my name to this specification.

DR. KOLOMAN RÓKA.
